UNITED STATES PATENT OFFICE.

CHRISTIAAN W. AVELING, OF LOCKPORT, ILLINOIS, ASSIGNOR TO JULIA AVELING,
OF LOCKPORT, ILLINOIS.

HOISTING MACHINERY.

Application filed September 8, 1922. Serial No. 586,864.

To all whom it may concern:

Be it known that I, CHRISTIAAN W. AVELING, a citizen of the United States, residing at Lockport, in the county of Will and State of Illinois, have invented new and useful Improvements in Hoisting Machinery, of which the following is a full, clear, concise, and exact description, reference being had to the accompanying drawing, forming a part 10 of this specification.

My invention relates to hoisting machinery.

One of the objects of my invention is to provide an improved hoisting machine for 15 operating a grab bucket or the like in which a single motor is used for controlling both the holding drum and lacing drum, and in which provision is made whereby when the grab bucket is being closed it will be permitted to dig into the material being 20 handled, to permit the jaws to follow their own inclination in grasping the material.

A further object of my invention is to provide an improved hoisting mechanism in 25 which a single motor controls both the holding and lacing drum, in which a yielding tension is exerted on the holding rope during the grasping movement of the bucket whereby the starting of the holding drum, 30 when the bucket is closed, is facilitated.

A further object of my invention is to provide an improved hoisting machine in which a single motor controls both the holding and lacing drum, in which a delayed action or lost motion impositive drive is provided between the motor and holding drum, to prevent jerking and jarring and unevenness of operation when the motor takes hold 35 of the holding drum.

40 A further object of my invention is to improve the construction of the delayed action transmission mechanism.

Further objects will appear from the detailed description to follow and from the 45 appended claims.

In the drawings in which an embodiment of my invention is shown—

Figure 1 is a side elevation of a trolley;

Fig. 2 is a side elevation of the other side 50 of the trolley;

Fig. 3 is a plan view of the trolley with part of the transmission shown in section;

Fig. 4 is an end elevation of the trolley;

Fig. 5 is an axial sectional view of the 55 transmission between the motor and drums;

Fig. 6 is a section on the line 6—6 of Fig. 4;

Fig. 7 is a section on the line 7—7 of Fig. 5; and

Fig. 8 is a section on the line 8—8 of Fig. 5.

The construction shown in the drawing comprises a trolley 10, mounted to run on the track 11, the trolley having the trolley sides 12, mounted on the trolley wheels 13 which travel on the track 11. A suitable motor and transmission (not shown) is provided for acting on the trolley wheels 13 to cause the trolley to travel back and forth on the rails 11 of the bridge. The trolley 70 shown is provided with a single lacing drum 14, which controls the opening and closing movement of the bucket 15, and with a divided holding drum having the drum portions 16 and 17 for supporting the bucket 75 15 during the opening movement of said bucket. A single motor 18 is provided for controlling both the lacing drum 14 and the holding drum portions 16 and 17, suitable transmission 19 being provided between the 80 motor 18 and the drums to effect the various movements of the holding and lacing drums which are necessary to the operation of the bucket.

The desired operation of the bucket is as 85 follows—Assuming that the bucket is loaded and that it is desired to elevate the bucket, transfer the load to a desired point, dump the bucket, bring the bucket back to the supply, and pick up another bucket full of material, with the bucket loaded as aforesaid, the motor is operated to raise the bucket, the motor 18 acting on both the lacing and holding drum to raise the bucket, and the trolley and bridge are moved along their track to 90 bring the bucket to the position desired for dumping. The hoist motor is then reversed to dump the bucket. As soon as the motor is reversed, a pair of pawls 20 and 21 (Fig. 2) are automatically thrown in which act 100 through a friction holding device to hold the holding drum against movement, the delayed action transmission between the motor and the holding drum permitting a slackening of the lacing drum to permit the bucket to 105 dump without any movement of the holding drum.

As soon as the lost motion between the motor and the holding drum has been taken up, the friction holding device which holds the 110

holding drum against movement is loosened up, and further action of the motor results in lowering of the bucket under its own weight. The trolley and bridge are caused to travel back to the loading point, and the bucket is lowered in open position down on the material to be handled.

When the bucket has been lowered sufficiently to be in the right position to grasp 10 another load, the motor is again reversed. Immediately upon reversal of the motor the pawls 20 and 21 are thrown out to permit the holding rope to be paid out, if the action of the bucket in grasping the load demands or requires such action. The motor then causes the lacing drum to act to close the bucket to cause it to grasp a load. During this closing movement of the bucket, a yielding force is exerted on the holding rope 20 also, by means of spring-pressed friction devices, this tension on the holding rope not being sufficient to raise the bucket against its own weight, and not being sufficient to prevent the jaws from following their own 25 inclination in digging into and grasping material, but being sufficient to maintain the holding rope taut and to prevent the bucket from flopping around or tipping over on its side. When the grasping movement of the bucket is complete and the bucket has closed on its load, the lost motion transmission to the holding drum has been taken up, and continued action of the motor raises the bucket in closed position carrying 30 the load. The pawls 20 and 21 which are released immediately upon rotation of the motor in a hoisting direction, and which are automatically thrown in upon movement of the hoist motor in a lowering direction, are provided in duplicate for the sake 35 of safety, so that if even one of them fails to act, the chances are that the other will act. These pawls are controlled in their movement by the transmission to the lacing drum, (as distinguished from the transmission to the holding drum) so that they are thrown in or out depending upon the direction which the lacing drum is rotated. When the lacing drum is rotated in a direction 40 to close the bucket or raise the bucket, the pawls are thrown out, while when the lacing drum is turned in a direction to open the bucket or lower the load the pawls are thrown in. The construction by which this 45 is accomplished will be described more in detail hereinafter.

As intimated above, the lacing drum 14 is always directly connected with the motor, no lost motion transmission being provided 50 between the motor and this lacing drum. The transmission from the motor to the lacing drum comprises the motor pinion 22, the gear 23 meshing with the pinion 22, a built-up sectional tubular housing and transmission casing 24, on one end of which the

gear 23 is mounted, and on the other end of which is formed a pinion 25, and a drum gear 26 meshing with the pinion 25.

The transmission from the motor to the holding drum is the same as the transmission from the motor to the lacing drum up as far as the casing and transmission member 24. From here on the transmission to the holding drum comprises a delayed action or lost motion frictional drive or transmission 70 75 27 housed in the housing member 24, a shaft 28 extending through the housing member 24, and driven from the lost motion friction transmission 27, a unidirectional drive or transmission 29, driven from the shaft 28, a pinion 30, driven from the transmission 29, and the drum gear 31 driven from the pinion 30.

The unidirectional friction transmission 29 is so constructed that it can drive positively in only one direction so that lowering action of the holding drum can be accomplished only under the action of the weight of the bucket itself. Furthermore, means are provided for holding the holding drum against lowering movement during the dumping of the bucket, (that is to say, during the time that the lost motion transmission is being taken up) these holding means comprising the pawls 20 and 21 previously referred to, which engage ratchet teeth 32, formed on the casing member 33. This casing member 33 serves as a container for the unidirectional frictional drive, and also serves as a positioning means for certain of the friction discs 34 of this transmission, these friction discs 34 having peripheral lugs 35, which extend into longitudinal grooves 36 in the casing 33, whereby relative rotation between these frictional discs and the casing 33 is prevented.

The friction discs are controlled by a pair of spreader members 37 and 38, having helical engaging surfaces at 39 whereby relative rotation between the spreader members 37 and 38 in one direction will force the spreader members apart and relative rotation in the other direction will permit them to approach each other. One of these spreader members 37 is keyed to the drive 110 shaft 28 hereinbefore referred to, while the other spreader member 38 is keyed to the tubular extension 40 of the holding drum pinion 30. Intermediate friction discs 41 and 42 are provided mounted on the spreader members 37 and 38 respectively. These intermediate friction discs 41 and 42 are provided with inwardly extending lugs 43 (Fig. 7) which extend into longitudinally 115 extending grooves 44 and 45, formed in the spreader members 37 and 38 respectively, so that relative rotation between the discs 41 and 42 and the spreader members 37 and 38 is prevented.

The casing 33 serves to "back up" the fric- 120 125 130

tion discs when they are spread apart by the action of the spreader members 37 and 38, the friction discs being then clamped between the ends of the casing 33 and the respective spreader members 37 and 38. The expanding action of the spreader member takes place on the raising movement of the bucket. On the raising movement of the bucket, the spreader members 37 and 38, the 10 friction discs 41 and 42, and the casing member 33 are all clamped together as a unitary device, so that the holding drum pinion 30 rotates along with the spreader member 45.

During the dumping of the bucket, the 15 shaft 28 and spreader member 37 remain idle, because of the lost motion transmission, to be described more in detail hereinafter, and the spreader members, friction discs, holding pinion 30 and casing 33 are held 20 stationary by the action of the holding pawls 20 and 21 which engage the teeth 32 of the casing 33 as described above.

At the end of the dumping action, the lost motion transmission to the holding drum has 25 been taken up, and the shaft 28 is then caused to rotate in a lowering direction. The spreader 37 which is keyed to the shaft 28 is thus rotated in a direction to loosen up the spreader members and the friction discs 30 in the casing 33, and this permits the spreader member 38 to follow along with the spreader member 37, this follow-up action of the friction disc being due to the weight 35 of the bucket acting on the holding drum, this force being transmitted to the spreader member 38, through the pinion 30, and the extension sleeve 40 on the pinion 30.

When the open bucket is lowered onto the material to be handled, and the motor is 40 then reversed to cause the bucket to grasp the load, the reversing of the motor will automatically cause the pawls 20 and 21 to be thrown out of engagement with the ratchet teeth 32 as will be explained more 45 in detail hereinafter.

Also, as will be explained more in detail hereinafter, during the closing or grasping movement of the bucket, an impositive frictional force is being exerted on the shaft 28, 50 tending to rotate it in a direction corresponding to the hoisting movement of the holding drum. This tendency of the shaft 28 to rotate is sufficient to cause the spreader member 37 to bind the friction discs 35, 41 and 42 55 and clamp them together to cause a force to be exerted tending to rotate the holding drum pinion 30 in a hoisting direction. There is thus an impositive yielding force exerted on the holding drum, and hence on the holding rope, tending to raise the bucket. This impositive frictional force, however, as 60 will be explained hereinafter, can be adjusted and is so adjusted that it will not be sufficient to raise the bucket, but will simply 65 keep the bucket in proper position for grasp-

ing the load, and prevent it from falling over on its side or rolling down the side of the pile of material.

The releasing of the pawls 20 and 21 upon the reversal of the motor to cause the bucket 70 to pick up its load, releases the casing or drum 33, so that if a sufficient force is exerted on the holding rope (due to the action of the bucket in digging into the material) to overcome the impositive frictional 75 force exerted thereon as described above, it will cause the holding rope to be unwound. The advantage of this releasing of the pawls during the loading of the bucket is that it permits the bucket to act naturally in picking up its load, permitting the bucket to dig into the material being handled, and the jaws to follow their own inclination in grasping the material, which would not be the case if the holding rope were fixedly 80 held.

Coming now to a description of the impositive lost motion friction drive 27 contained in the casing 24, the lost motion or delayed action part of this construction comprises a pair of sleeves 46 and 47 respectively, the sleeve 46 being smaller in diameter than the sleeve 47 and being threaded inside it. The sleeve 46 has a feathered engagement with the shaft 28, while the sleeve 90 47 has a feathered engagement with the casing 24, this feathered engagement permitting longitudinal movement of the sleeves but preventing relative rotation between them and the members on which they are 95 feathered. The two sleeves are thus "floatably" mounted with respect to the shaft 28 and the casing 24, so that they can move 100 longitudinally with respect to these members but cannot rotate with respect to the member on which they are feathered. The two members together thus constitute an expandable and contractible device which is made use of to bind or release a pair of 105 friction disc sets 48 and 49. One set of friction discs is located at each end of the sleeve, the sleeves acting equally and in opposite directions on these sets, the floatable mounting of the sleeves permitting the sleeves to adjust themselves, so that they 110 will bear equally on the two sets. Because of the fact that the sleeves are floatably mounted and the discs made in two different sets located at opposite ends of the floatable 115 expandable device, I am enabled to make use of both sets of discs, both on the raising and lowering movement of the hoist as will be explained more in detail hereinafter, which would not be the case if the expandable element were not floatably mounted and did not act between two sets of friction discs. 120 As shown in Fig. 5 each set 48 and 49 of the friction discs comprises an intermediate friction disc 50 feathered on the shaft 28, 125 and engageable by the inner sleeve 46 and 130

a pair of outer friction discs 51 feathered on the casing 24 and engageable by the outer threaded sleeve 27.

In order to produce the impositive force hereinbefore referred to which causes a tendency of the holding drum to rotate during the closing movement of the bucket, two sets of spring friction devices are provided for pressing the discs 51 and 50 together. Each of these sets as shown in Figs. 5 and 8 comprises a number of spring-pressed cups or plungers 52 engaging the friction discs 51 and pressed thereagainst by means of the coil compression springs 53, the tension of which may be adjusted by means of the adjusting screws 54. This yielding pressure of the spring-pressed cups or plungers 52 presses the friction discs against each other so that an impositive force is transmitted through these friction discs from the drive and casing member 24 to the shaft 28. This impositive force causes a tendency of the holding drum to be rotated in a direction to tighten the holding rope during the closing movement of the grab bucket. At the end of the closing movement of the grab bucket, the sleeves 46 and 47, due to their threaded engagement with each other, have moved into extended position so that the sleeve 46 will be bearing against the disc 50 of the one set of friction discs, and the outer sleeve 47 will be bearing against the disc 51 of the other set of friction discs. This causes a further increase in the friction between the friction discs increasing the hoisting action on the holding rope and causing the holding rope to assist the lacing rope in raising the bucket.

Due to the fact that during the closing movement of the bucket the spring-pressed cups 52 cause a tension in the holding rope, there is no considerable shock or jar when the tension in the holding rope is increased by the action of the threaded sleeves 46 and 47. Furthermore, the additional tension in the holding rope due to the action of the sleeves 46 and 47 is increased gradually, not abruptly, because of the cooperation of the spring-pressed plungers 52, which allows the plate 51 to yield under the spreading action of the sleeves 46 and 47. The fact that before the sleeves 46 and 47 get in their action there is already a tension in the holding rope and the fact that the tension due to the spreading of the members 46 and 47 increases gradually makes it so that there is no appreciable shock or jar in starting up the holding drum.

It will be noted that the threaded sleeves 46 and 47 are "double acting" in that they act as a lost motion or a delayed action device both during the grasping and during the dumping action of the bucket. This double action is accomplished by making the threaded connection between the two

sleeves such that the inner sleeve can thread its way entirely through the outer sleeve so that during the grasping action of the bucket the inner threaded sleeve engages the disc 50 of one set, and during the dumping action of the bucket it engages the disc 50 of the other set of friction discs, the engagement of the outer sleeve 47 with respect to the discs 51 being also correspondingly reversed.

The mechanism for controlling the pawls 20 and 21 will now be described. As stated above, two pawls are provided for the sake of safety, so that it is not likely that both of them will fail to act at the same time. The control for both pawls is similar, both being controlled by means of friction rings mounted on the casing 24 which drives the lacing drum. The pawl 20 is, as shown in Figs. 2 and 6, mounted on a rock-shaft 55, a segmental pinion 56 being mounted on the other end of the rock-shaft, which pinion meshes with the segmental gear 57 formed as a part of the friction ring 58, which is mounted in an annular groove 59 in the transmission casing 24. In a similar manner, the pawl 21 is mounted on a rock-shaft 60, on the other end of which is mounted a segmental pinion 61, meshing with a segmental gear 62 (Fig. 4) formed as a part of the friction ring 63 which is mounted in the groove 64 of the transmission casing 24. Suitable adjusting screws 65 are provided for securing the right amount of friction between these friction rings 58 and 63 and the casing or drum on which they are mounted. With this construction, when the transmission drum 24 is turned in a direction to cause hoisting movement of the lacing drum the pawls 20 and 21 are thrown out of engagement with the ratchet 32, and when the transmission casing is rotated in a direction to slacken the lacing rope, the pawls 20 and 21 are thrown into engagement with the ratchet 32. Thus in dumping, when the lacing rope is slackened (the holding drum in the meantime not being rotated because of the lost motion transmission) the pawls 20 and 21 are thrown into engagement with the ratchet 32, and this prevents any lowering motion of the holding drum until the delayed action of the transmission has been taken up, so that the holding drum holds the bucket suspended while the lacing rope is slackened to permit the bucket to open to dump the load. The pawls 20 and 21 remain in engagement with the ratchet 32 during the lowering of the bucket, but as soon as the delayed action transmission has been taken up, the holding drum is lowered due to the weight of the bucket, as the spreader members 38 and 39, as soon as this delayed action transmission is taken up, cease to bind the friction discs, and the spreader 38 follows up the spreader member 39 due to the

weight of the bucket. The bucket is thus lowered in open position until it is ready to pick up another load. The motor is then reversed, causing the lacing drum to be wound up to cause the closing of the bucket, and at the same time causing the pawls 20 and 21 to be thrown out to permit the ratchet wheel 32 to rotate, if necessary, to allow the holding rope to be paid out and permit the bucket to follow its own inclination in digging into the material, the holding drum, however, remaining taut because of the frictional plungers or cups 52.

The segmental pinions 56 and 61 remain always in mesh with the segmental gears 57 and 62, respectively, as the movement of the pawls is slight.

In dumping, it is necessary that the friction discs 50 and 51 shall be released prior to the release of the friction discs 35, 41 and 42, otherwise, it might happen that the bucket would be lowered in closed position and could not be dumped. In order to insure that the friction discs 50 and 51 will be released prior to the release of the discs 35, 41 and 42, I may provide adjustable friction plungers or cups 66 similar to the cup 52, these cups 66 being spring-pressed against the disc 41 by means of a coil compression spring 67, the tension of which may be adjusted by an adjusting screw 68. By adjusting the screws 68 any desired pressure may be exerted on the disc 41 to insure that this set of discs will not be released before the discs 50 and 51.

The motor 18 is provided with any suitable type of magnetic brake 64 which is thrown on automatically when the current is turned off from the motor, in the usual manner of magnetic brakes. This, of course, holds the lacing drum 14 against movement when the current is turned off from the motor and prevents the bucket from dumping before the operator is ready; that is, before he reverses the motor to unwind the lacing rope.

Having thus described my invention, what I claim as new and desire to secure by Letters Patent of the United States is—

1. A hoisting machine comprising a releasable load-grasping device, a holding drum, a lacing drum for controlling the releasing and grasping of said load-grasping device, a single motor for controlling both of said drums, transmission means between said motor and said drums including a delayed action transmission between the motor and holding drum, whereby the lacing drum may be given a limited movement, without any movement of the holding drum, to control the grasping and releasing of said load-grasping device, said transmission means including also an impositive drive between said motor and holding drum whereby in grasp-

ing the load an impositive force is exerted on the holding rope, permitting the holding rope to pay out, to allow the grasping device to dig into the material to be loaded, and exerting a yielding force to facilitate starting the movement of the holding drum, said transmission means including also a positive drive between the motor and the holding drum and means whereby said impositive drive is effective during the grasping operation of the load grasping device and whereby said positive drive is effective during the raising movement of the load.

2. A hoisting machine comprising a releasable load-grasping device, a holding drum, a lacing drum for controlling the grasping and releasing of the load-grasping device, a single motor for controlling both of said drums, transmission means between said motor and said drums, including a delayed action transmission between the motor and holding drum, whereby said lacing drum may be given a limited movement without any movement of the holding drum, to control the grasping and releasing of said load-grasping device, an automatically acting brake for holding said holding drum against movement when the lacing drum is releasing the load-grasping device, said transmission means including also means for exerting an impositive force on the holding drum tending to raise the load-grasping device during the grasping of the load, whereby in grasping the load an impositive force is exerted on the holding rope permitting the grasping device to dig into the material to be handled, and whereby the starting of the movement of the holding drum is facilitated, said transmission means including also a positive drive between the motor and the holding drum and means whereby said impositive drive is effective during the grasping operation of the load grasping device and whereby said positive drive is effective during the raising movement of the load.

3. A hoisting machine comprising a releasable load-grasping device, a holding drum, a lacing drum for controlling the grasping and releasing of the load-grasping device, a single motor for controlling both of said drums, and transmission means between said motor and said drum including a delayed action transmission between the motor and holding drum, whereby said lacing drum may be given a limited movement without any movement of the holding drum, to control the grasping and releasing of said load-grasping device, said transmission means comprising a rotatable driving element for the lacing drum, a rotatable driving element for the holding drum, a sleeve slidably keyed to said lacing drum driving element, a sleeve slidably keyed to said holding drum driving element, said sleeves having screw-threaded

- engagement with each other, and being float- 65
ably mounted with respect to said driving
elements and friction elements engaged by
said sleeves.

5. A hoisting machine comprising a re-
leasable load-grasping device, a holding
drum, a lacing drum for controlling the
grasping and releasing of the load-grasping
device, a single motor for controlling both of
10 said drums, and transmission means between
said motor and said drum including a de-
layed action transmission between the motor
and holding drum, whereby said lacing drum
15 may be given a limited movement without
any movement of the holding drum, to con-
trol the grasping and releasing of said load-
grasping device, said transmission means
comprising a rotatable driving element for
20 the lacing drum, a rotatable driving element
for the holding drum, a sleeve slidably keyed
to said lacing drum driving element, a sleeve
25 slidably keyed to said holding drum driving
element, said sleeves having screw-threaded
engagement with each other, and being float-
ably mounted with respect to said driving
elements, friction elements engaged by said
30 sleeves, there being two sets of friction ele-
ments, and said sleeve being located inter-
mediate said sets of friction elements.

30. 5. A hoisting machine comprising a re-
leasable load-grasping device, a holding
drum, a lacing drum for controlling the
grasping and releasing of the load-grasping
device, a single motor for controlling both of
35 said drums, and transmission means between
said motor and said drum including a de-
layed action transmission between the motor
and holding drum, whereby said lacing drum
40 may be given a limited movement without
any movement of the holding drum, to con-
trol the grasping and releasing of said load-
grasping device, said transmission means
comprising a rotatable driving element for
45 the lacing drum, a rotatable driving element
for the holding drum, a sleeve slidably keyed
50 to said lacing drum driving element, a sleeve
55 slidably keyed to said holding drum driving
element, said sleeves having screw-threaded
engagement with each other, and being floatably mounted with respect to said driving elements, and friction elements engaged by said sleeves, there being two sets of friction elements, said sleeve being located intermediate said sets of friction elements, said inner sleeve being capable of being threaded completely through said outer sleeve, whereby in hoisting the outer sleeve will engage one set of friction elements, and the inner sleeve the other set of friction elements, and in lowering the relation will be reversed.

6. A hoisting mechanism comprising a re-
leasable load-grasping device, a holding
drum, a lacing drum for controlling the

grasping and releasing of the load-grasping device, a single motor for controlling both of said drums, transmission means between said motor and said drums, including a delayed action transmission between the motor and holding drum, whereby said lacing drum may be given a limited movement without any movement of the holding drum to control the grasping and releasing of said load-grasping device, said transmission means including also a positive drive between the motor and the holding drum and means whereby said impositive drive is effective during the grasping operation of the load grasping device and whereby said positive drive is effective during the raising movement of the load, means for holding said holding drum against movement when the lacing drum is releasing the load-grasping device, comprising a rotatable member, means for preventing rotation of said rotatable member during the releasing of said load-grasping device, and means operated automatically upon the reversal of the motor for rendering said rotation preventing means ineffective during the load-grasping movement of the lacing drum, whereby said holding drum is released from the control of said rotation preventing means to permit the holding rope to pay out, to allow the load-grasping device to dig into the material being handled.

7. A hoisting mechanism comprising a re-
leasable load-grasping device, a holding
drum, a lacing drum for controlling the
grasping and releasing of the load-grasping
device, a single motor for controlling both of
100 said drums, transmission means between
said motor and said drums, including a de-
layed action transmission between the motor
and holding drum, whereby said lacing drum
105 may be given a limited movement without
any movement of the holding drum to con-
trol the grasping and releasing of said load-
grasping device, said transmission means in-
cluding also a positive drive between the
110 motor and the holding drum and means
whereby said impositive drive is effective
during the grasping operation of the load-
grasping device and whereby said positive
115 drive is effective during the raising move-
ment of the load, means for holding said
holding drum against movement when the
lacing drum is releasing the load-grasping
device, comprising a rotatable member, means
120 including a ratchet and pawl for pre-
venting rotation of said rotatable member
during the releasing of said load-grasping
device, and means, including means operated
automatically upon the reversal of the motor
125 for moving the pawl out of engagement with
the ratchet, for rendering said rotation pre-
venting means ineffective during the load-
grasping movement of the lacing drum,

whereby said holding drum is released from the control of said rotation preventing means to permit the holding rope to pay out, to allow the load-grasping device to dig 5 into the material being handled.

8. A hoisting mechanism comprising a releasable load-grasping device, a holding drum, a lacing drum for controlling the grasping and releasing of the load-grasping 10 device, a single motor for controlling both of said drums, transmission means between said motor and said drums, including a delayed action transmission between the motor and holding drum, whereby said lacing drum 15 may be given a limited movement without any movement of the holding drum to control the grasping and releasing of said load-grasping device, said transmission means including also a positive drive between the 20 motor and the holding drum and means whereby said impositive drive is effective during the grasping operation of the load grasping device and whereby said positive drive is effective during the raising movement 25 of the load, means, including an automatic brake, for holding said holding drum against movement when the lacing drum is releasing the load-grasping device, comprising a rotatable member, means for preventing 30 rotation of said rotatable member during the releasing of said load-grasping device, and means operated automatically upon the reversal of the motor for rendering said 35 rotation preventing means ineffective during the load-grasping movement of the lacing drum, whereby said holding drum is released from the control of said rotation preventing means to permit the holding rope to pay out, to allow the load-grasping device to dig into 40 the material being handled.

9. A delayed action friction drive comprising a driving member, a driven member, a sleeve floatably keyed on said driving member, a sleeve floatably keyed on said 45 driven member and having a screw-threaded engagement with said other sleeve, and friction members engaged by said sleeves and acting as transmission between said driving member and said driven member.

50 10. A delayed action friction drive comprising a driving member, a driven member, a sleeve floatably keyed on said driving member, a sleeve floatably keyed on said driven member and having a screw-threaded engagement with said other sleeve, and friction members engaged by said sleeves and 55 acting as transmission between said driving member and said driven member, said friction members comprising two sets of fric-

tion discs, said sleeves being mounted intermediate said discs.

11. A hoisting mechanism comprising a releasable load-grasping device, a holding drum, a facing drum for controlling the grasping and releasing of the load-grasping 65 device, a single motor for controlling both of said drums, transmission means between said motor and said drums, including a delayed action transmission between the motor and holding drum, whereby said lacing drum 70 may be given a limited movement without any movement of the holding drum to control the grasping and releasing of said load-grasping device, means for holding said holding drum against movement 75 when the lacing drum is releasing the load-grasping device, comprising a rotatable member, means including a ratchet and pawl for preventing rotation of said rotatable member during the releasing of said load- 80 grasping device, and means, including means for moving the pawl out of engagement with the ratchet, for rendering said rotation preventing means ineffective during the load-grasping movement of the lacing drum, 85 whereby said holding drum is released from the control of said rotation preventing means to permit the holding rope to pay out, to allow the load-grasping device to dig into the material being handled, said pawl being controlled by the transmission to the lacing 90 drum.

12. A hoisting machine comprising a releasable load-grasping device, a holding drum, a lacing drum for controlling the 95 grasping and releasing of the load-grasping device, a single motor for controlling both said drums, transmission means between said motor and said drum including a lost motion friction transmission between the motor and holding drum whereby said lacing drum 100 may be given a limited movement without the movement of the holding drum to control the grasping and releasing of the load-grasping device, a unidirectional frictional transmission between the said lost motion friction transmission and said holding drum, means for operating on the unidirectional transmission to hold said holding drum against lowering movement during the dumping of the load, and means whereby on releasing the load-grasping device the lost motion frictional transmission 105 will be released in advance of the unidirectional frictional transmission.

In witness whereof, I have hereunto subscribed my name.

C. W. AVELING.
